LE ROY A. CRUMLEY

HANGING LANTERN

Filed Jan. 29, 1927

Inventor

Le Roy A. Crumley

By his Attorney John D. A. G.

UNITED STATES PATENT OFFICE.

LE ROY A. CRUMLEY, OF NEW YORK, N. Y., ASSIGNOR TO HARRY M. FELTENSTEIN, OF NEW YORK, N. Y., DOING BUSINESS AS M. EISENBERG & SON.

DESIGN FOR A HANGING LANTERN.

Application filed January 29, 1927. Serial No. 20,532. Term of patent 3½ years.

To all whom it may concern:

Be it known that I, LE ROY A. CRUMLEY, a citizen of the United States, and a resident of New York, county of Bronx, and State of New York, have invented a new, original, and ornamental Design for a Hanging Lantern, of which the following is a specification, reference being had to the drawing forming a part hereof.

The figure in the drawings shows a side elevational view of the hanging lantern.

I claim:

The ornamental design for a hanging lantern substantially as shown.

LE ROY A. CRUMLEY.
